UNITED STATES PATENT OFFICE

CHARLES A. MOORE, OF EDINA, MINNESOTA

REFRIGERATING AND VENTILATING APPARATUS

Application filed September 12, 1930. Serial No. 481,426.

My invention relates generally to refrigerating and ventilating apparatus for storage chambers for perishable lading, such as the lading chambers of storage houses, terminal structures, ships, etc., but it relates more particularly to refrigerating and ventilating apparatus for the lading chambers provided within the bodies of trucks and trailers used in highway transportation and for such chambers within the cars of railway trains.

An object of my invention is to provide improved and simplified means arranged in conjunction with a storage chamber, whereby the air within such chamber may be effectively and economically conditioned in a manner to preserve perishable lading stowed within the chamber.

Another object of the invention is to provide a circulatory refrigerating system for a storage chamber wherein a refrigerating liquid is caused to be circulated by means of compressed fresh air which is washed during its liquid propelling action and thereafter introduced into the chamber for ventilating purposes.

Another object of my invention is to provide simple and effective means for exhausting air from the storage chamber and, further, to provide a simple arrangement whereby the air within the chamber is effectively circulated therein, by gravity.

An additional object is to supply an apparatus, as above, which is susceptible of unit duplication within the bodies of trucks and trailers and within the cars of railway trains, the various units in a given train selectively receiving their compressed fresh air supply from a source accumulated and stored in the truck, engine, or other vehicle of the train.

With the foregoing and other objects in view, which will appear in the following description, the invention resides in the novel combination and arrangement of parts and in the details of construction hereinafter described and claimed.

In illustrating an application of my invention, I have shown an embodiment thereof of including one form of apparatus in conjunction with the bodies of a truck and trailer for highway traffic.

In the drawings, Fig. 1 is a fragmentary view illustrating the forward portion of a truck, partly in plan and partly in section, the part in section being taken as on the line 1—1 of Fig. 3, said view, as well as others 55 hereinafter mentioned, showing a part of my apparatus as it is applied to the vehicular structure; Fig. 2 is a fragmentary view illustrating the rear portion of the truck shown in Fig. 1 and the forward portion of a trailer 60 attached to said truck, said view being primarily a plan sectional view taken as on the line 2—2 of Fig. 4; Fig. 3 is a fragmentary view corresponding with Fig. 1, the same being partly in elevation and partly in section, the sectional part being taken as on the line 3—3 of Fig. 1; Fig. 4 is a fragmentary view corresponding with Fig. 2 and is in vertical section, being taken as on the line 4—4 of Fig. 2; Fig. 5 is a transverse vertical 70 sectional view taken as on the line 5—5 of Fig. 3; Fig. 6 is an elevational view in detail illustrating the connection between the air supply tank and the return riser of the refrigerant circulating pipe, and Fig. 7 is an enlarged view, partly in section, showing in detail the air jet and its location within said riser.

Reference being had to the drawings, it will be seen that I have illustrated a truck A 80 and a trailer B attached thereto. The truck includes the usual chassis frame 10, front and rear wheels 11, 12 and engine 13, the body of said truck comprising an insulated floor 14, side walls 15, roof 16, front wall 17, and a 85 rear wall 18 with a door opening therein. This insulated body provides a storage chamber X which is accessible at the rear through insulated doors 19 fitted to the door opening in the rear wall 18.

The trailer B includes the usual chassis frame 20, supporting wheels 21 and an insulated body similar to that of the truck and consisting of an insulated floor 22, side walls 23, end walls 24 and roof 25. The front wheels 21 of the trailer B are connected through a suitable tongue or draw bar 26 with a coupling member 27 secured to the rear of the truck chassis. The body of the trailer B, like that of the truck A, provides 100

an insulated lading chamber X, it being within the contemplation of my invention to employ as many trailers as may be desired.

Within the truck body and traversing the chamber X therein is a partition wall 28 which falls short of the ceiling of the chamber at the top thereof and short of the floor of the chamber at the bottom thereof, said partition wall providing a compartment W within the forward end of the truck body, the same communicating at the upper portion thereof with the upper portion of the chamber X, through a passageway 29 formed above the partition wall 28, and at the lower portion thereof with the lower portion of said chamber, through a passageway 30 formed beneath the partition wall. Within this compartment W is an upright tank 31 open at the top thereof, the forward side of said tank being spaced from the front wall 17 of the truck body, the rear side thereof being spaced from the partition wall 28 and the ends being spaced from the side walls 15 of said truck body. The tank 31 is supported with the bottom thereof elevated substantially above the floor 14 of the truck, said tank resting upon strips 32 disposed transversely of the truck body and supported upon stringers 33 positioned lengthwise of the truck. Lading within the chamber rests upon a false floor consisting of spaced floor strips 34 laid on spaced cleats 35 which are supported upon stringers 36 extending longitudinally along the floor 14 of the truck, the space between the floor 14 proper and the floor strips 34 constituting a sub-chamber V, into which air gravitates from the compartment W, through the passageway 30, and from which air ascends into the chamber X, through the spaces between said floor strips 34. A pipe 37 for conveying a liquid refrigerant from the tank 31 is looped back and forth in the sub-chamber V, between the stringers 36, one extremity of said pipe being connected with the tank 31 at bottom thereof, the outer extremity of said pipe constituting a return riser 37^a discharging into the tank 31 at the top thereof. In the pipe 37 at a point near the tank 31 is a cut-off valve 38 and depending from said pipe is a branch pipe 38^a, fitted with a valve 39, by means of which the tank 31 and pipe 37 may be drained of their contents.

The refrigerating liquid which is supplied to tank 31 may be of any suitable character, such as cold brine or the like, and to such liquid may be added a quantity of ice, the hatches 40 in the roof 16 of the truck body providing for the ready introduction thereof into said tank.

With the tank 31 charged with ice and brine and the pipe 37, in turn, charged with brine from the tank, a circulation of air, by gravity, is set up within the truck body. The air in the compartment W surrounding

the tank 31 is cooled and descends in the said compartment passing through the passageway 30 into the sub-chamber V where it is further cooled by reaches of the pipe 37. This refrigerated air in the sub-chamber V thence rises between the floor strips 34 and through the lading stowed therein, the same taking the place of the air ascending in the chamber X about the lading and along the relatively warm side walls of the truck body. Reaching the upper portion of the chamber X, the air passes through the passageway 29 and into the upper portion of the compartment W to take the place of the air cooled about said tank and descending in said compartment by gravity.

The refrigerating liquid in the pipe 37, supplied thereto from the supply in the tank 31, is caused to circulate through said pipe by introducing air under pressure into the return riser 37^a, as by means of a jet or nozzle 41 (Fig. 7) disposed within said riser. This nozzle or jet 41 may be applied to the riser 37^a in any suitable manner, the method shown involving the threading of the base of the jet into a hollow internally threaded boss 42 formed in an elbow 43 connecting the pipe 37 proper with the return riser 37^a. An air lead 44 for feeding air to said jet is threaded into said boss 42 as shown in Fig. 7, said lead being looped upwardly above the high liquid level in the tank 31 and connected with one end of an air storage tank 45, resting upon the floor of the truck, crosswise thereof and beneath the stringers 33 supporting the tank 31. This air lead 44 is fitted with a cut-off valve 46 by means of which the flow of air therethrough may be regulated. Feeding into the opposite end of the air storage tank 45 is an air pipe 47 leading from an air compressor 48 suitably supported by the truck chassis, said feed pipe 47 being fitted with a safety valve 49 of suitable construction and a cut-off valve 50. The air compressor 48 is driven through a shaft 51 from a power take-off device 52 of suitable construction, which is operated in the usual manner from the engine 13 of the truck A.

Air entering the return riser 37^a, through the jet 41, causes the liquid therein to rise above its normal level, co-incident with the level of the liquid in the tank, and to flow from the upper end of said riser into the open tank 31 at the top thereof, said end of said riser being bent, as shown to thus conduct the liquid expelled from the riser. As the upwardly moving air from the jet 41 commingles with the liquid in the riser 37^a, it is washed and cooled by said liquid and, upon finding its exit from the riser, it enters the upper portion of the compartment W in a washed and refrigerated condition. This washed, refrigerated air commingling with the air in the upper portion of the compartment W.

ment W freshens and cools the downward flow of air with which it is united and, with such air it is further refrigerated in its downward passage along the sides and ends of the tank 31, preparatory to its introduction to the sub-chamber V and the lading chamber X.

Corresponding to the quantity of fresh air introduced into the chamber X through the jet 41, an equal amount of air finds exit from the chamber X by way of leakage through the truck body or through an upright air egress conduit 53, which I have provided to conduct air from the upper portion of the compartment W where the relatively warm air enters from the upper portion of the chamber X. This upright conduit 53 is located in the space between one end of the tank 31 and the adjacent side wall 15 of the truck body. The upper end of said conduit 53 falls short of the ceiling of the compartment W, while the lower end thereof projects through the floor 14 and opens into the atmosphere beneath the truck, control of the escape of air through said conduit 53 being had by means of a damper 54 arranged within said conduit and provided with a handle 55 accessible from the cab of the truck.

In order to provide for the introduction of fresh air into the chamber X at such times as it may be undesirable to operate the compressor 48 through the truck engine, I have arranged within the compartment W an upright air ingress conduit 56, the same opening at its upper end through a side wall 15 of the truck body into the outer atmosphere and at its lower end into the interior of the compartment W. By reason of its proximity to the tank 31 and of its location in the downward stream of cold air about said tank, the air in this upright ingress conduit is cooled and thereby caused to descend from the outer atmosphere into said compartment. This ingress of fresh air, by gravity, into the circulating flow of air within the truck body may supplement the inflow of fresh air thereto from the air jet 41 in the liquid return riser 37^a. A damper 57 is arranged within the ingress conduit 56 and operated by a handle 58 accessible from the cab of the truck to shut or control the ingress of air through said conduit 56.

The unitary circulatory system incorporated within the truck body, as above described, with few exceptions, is duplicated in the trailer body, the corresponding parts of said duplicate systems being designated by similar reference characters. Thus, a full detailed description of the circulatory system within the trailer body will be unnecessary. One exception, above referred to, resides in the omission from the trailer body of a compressed air storage tank.

In lieu of such storage tank, the trailer B, and any succeeding trailer, is supplied with

an air line 59 extending from end to end thereof, the upwardly looped air lead 44 being connected with said air line 59. An air line 60 provided in the truck and fitted with a cut-off valve 61, connects at one end with the compressed air tank 45, the other end thereof being accessible at the rear of the truck. In connecting the air line 60 of the truck A with the air line 59 of the trailer B, I employ a hose or other suitable flexible connection 61. The air line 59 at the rear of the trailer is provided with a cut-off valve (not shown) which is either opened or closed according to the presence of absence of a succeeding trailer, comprising in its construction the features of my present invention. Thus, the several vehicles in a train are equipped with similar unitary circulatory systems, which may be severally operated, as desired, the system in each vehicular body operating to set up a convective circulation of refrigerated air in its respective lading chamber and to ventilate the chamber in an efficient manner.

From the foregoing, it is to be noted that numerous advantages reside in my invention, the refrigerating and air circulating and ventilating features residing in the unitary circulatory systems in vehicular or other lading chambers being highly desirable and highly efficient, the attendant cost of initial installation and of operation being comparatively small. The employment of air pressure, in accordance with my present invention, to cause and maintain the circulation of a liquid refrigerant in a unitary circulatory system readily lends itself to satisfactory adoption in the various vehicular structures of a train, it being relatively simple and practical to maintain a supply of air under pressure in a line throughout a train. And, as explained, I advantageously employ air from such a line as a motivating medium for causing and maintaining a circulation of liquid through the refrigerant conducting pipes. Additionally, my invention is advantageous by reason of the use to which the air is put after it is employed in its liquid motivating capacity. And this is true, particularly in structures employed in highway and railway traffic, as the air, which is washed and cooled in the process of causing the circulation of the liquid in the refrigerant conducting pipes, is thereafter employed in ventilating the lading chambers.

Changes in the specific form of my invention, as herein disclosed, may be made within the scope of what is claimed without departing from the spirit of my invention.

Having described my invention, what I claim as new and desire to protect by Letters Patent is:

1. In combination, a train of vehicular structures, each providing a storage chamber and a compartment adjacent thereto, the chamber being in communication at its up-

- per portion with the upper portion of the compartment and at its lower portion with the lower portion of said compartment, a unitary circulatory system within each structure, each system including an upright tank for a liquid refrigerant disposed within the compartment of its respective structure and spaced from the walls thereof and including a pipe for conveying the liquid from the lower portion of the tank along the bottom of said chamber and back to the upper portion of the tank, an air compressor carried and operated by one of the vehicular structures of the train, a storage tank for the compressed air carried by one of the vehicular structures, an air line in each structure adapted to be coupled at the ends thereof to the adjacent ends of the air lines of the adjacent structures, said air tank being connected with the air line of its respective vehicular structure, each of said unitary systems further including an air jet disposed within the liquid refrigerant conveying pipe thereof, said jet being connected with the air line of its respective vehicular structure, the air issuing from said jet causing the circulation of the liquid in said pipe, the liquid, in turn, washing and cooling the air, said air thereafter providing a cold freshening supply thereof for the storage chamber.
2. In combination, a structure providing a storage chamber and an adjacent compartment, the chamber being in communication at its upper portion with the upper portion of the compartment and at its lower portion with the lower portion of said compartment, a circulatory system within said structure including a tank for a liquid refrigerant disposed within the compartment and spaced from the walls thereof and including a liquid circulating pipe for conveying liquid from the lower portion of the tank along the bottom of said chamber and back to the tank, said pipe including a riser for returning the liquid into the tank above the level of the liquid supply therein, said system further including an air jet upwardly disposed within said riser, a source of air supply connected with and feeding said jet, the air issuing from the jet causing the liquid to flow from the return riser, thereby establishing a circulation of the liquid through said tank and pipe, the air being washed and cooled in its passage through said riser and thereafter exhausted into the upper portion of said compartment, thus serving to freshen and cool the air circulating by gravity through said compartment and the adjacent chamber.
3. In combination, a structure providing a storage chamber and an adjacent compartment, the chamber being in communication at its upper portion with the upper portion of the compartment and at a lower portion with a lower portion of said compartment, a circulatory system within said structure in-
- cluding a tank for a liquid refrigerant disposed within the compartment and spaced from the walls thereof and including a liquid circulating pipe for conveying liquid from the tank along the said chamber and back to the tank, said system further including means for introducing air under pressure into said pipe, whereby a circulation of the liquid is established in said pipe and whereby the air is washed and cooled in its passage through said pipe and thereafter exhausted from the tank into said compartment, said washed and cooled air serving to reduce the temperature of the air in said compartment and stimulate the gravitating circulation of air through said compartment and the communicating chamber.
4. In combination, a structure providing a storage chamber and a refrigerating compartment communicating therewith, whereby a gravitating circulation of air is set up through said chamber and compartment, an open circulatory system for a liquid refrigerant partially embodied within said chamber and partially within said compartment, means for introducing air under pressure into said circulatory system for circulating the liquid therein, said system opening for the egress of air therefrom into said refrigerating compartment.
- In testimony whereof I have affixed my signature.
- CHARLES A. MOORE.
